UNITED STATES PATENT OFFICE.

GEORGE A. KIMBALL AND LAURON H. KIMBALL, OF DAVIS CITY, PA.

DEEP-WELL PUMP.

SPECIFICATION forming part of Letters Patent No. 271,082, dated January 23, 1883.

Application filed May 19, 1882. (No model.)

To all whom it may concern:

Be it known that we, GEORGE A. KIMBALL and LAURON H. KIMBALL, of Davis City, McKean county, Pennsylvania, have invented 5 new and useful Improvements in Deep-Well Pumps; and we do hereby declare that the following is a full, clear, and exact description thereof, reference being had to the accompanying drawing and the letters or figures of 10 reference marked thereon.

In operating oil-wells it is necessary to explode heavy charges of nitro-glycerine or other powerful explosive in the oil-bearing rock to shatter and disintegrate it for the purpose of 15 enlarging the hole and opening the crevices, thereby allowing the more rapid influx of oil. The effect of the explosion is to reduce large quantities of the rock to fine sand or powder, and this sand causes much annoyance in pumping the well. Being drawn into the pump with 20 the fluid, it soon cuts out the packing of the valves and destroys even the metallic parts of the pump. Another difficulty arises in this wise: It being the common practice to pump 25 the wells but a part of the time and let them stand still the remainder, the sand, which mixes with the oil or water and is carried along with it, will, when the pump is stopped, settle 30 down to the bottom of the eduction-pipe upon the valves. In deep wells the amount of sand thus settling is often so great as to entirely prevent the moving of the valves, and is always destructive to the packing, valves, and 35 working-barrel.

35 The object of our invention is to provide a pump in which these difficulties are obviated, and the manner of accomplishing this end will appear from the following description, reference being had to the accompanying drawing, 40 which is a vertical central section in elevation of our improved pump.

A represents the working-barrel, within which works the tight-fitting hollow plunger B, carrying the working-valve C.

45 C' is the stationary or standing valve, which is raised above the bottom of the working-barrel and within the hollow plunger by the pipe C².

D is a casing considerably larger in diameter than the working-barrel, and surrounding it.

E is the eduction-pipe.

F is the anchor, reaching down below the pump.

G G are lugs or projections at the top of the working-barrel, serving to keep it in a 55 central position within the casing D and insuring it to occupy a position exactly below the end of the eduction-pipe.

H is a screw-threaded pin, to which rods are attached for working the piston. 60

I is a chamber between the outer surface of the working-barrel and the casing D.

L is a bushing of peculiar construction, into which is screwed the casing D, the working-barrel A, or a pipe supporting it, and the 65 pipe C².

M is a chamber between the inner surface of the working-barrel and the pipe C².

The casing D may be of any desired length, it being only necessary to observe that the top 70 of the working-barrel A and the standing valve C' must occupy nearly the position shown—that is, the top of the working-barrel must be somewhat below the top of the casing D, and the standing valve C' must be well up into the 75 hollow plunger. These relative positions can always be maintained, whatever be the length of the casing D, by placing pipes of the proper length below the working-barrel and standing valve and screwing them all into the common 80 bushing L. The top of the working-barrel is not connected with the casing D, the lugs G G only serving as guides, and free communication is allowed from the space above to that 85 below the lugs.

The operation of this pump is as follows: When the plunger B is raised fluid is drawn through the pipe C² and the valve C', and upon the descent of the plunger it is forced through the working-valve C, and thus by successive 90 strokes is raised to the surface. When the pump is stopped, as has been mentioned, the tubing or eduction pipe is full of fluid, and the sand and sediment suspended therein are deposited, falling down into the space or chamber I, between 95 the working-barrel and the outer casing, D, and there remain until the tubing be drawn, when it may be emptied out. Without this chamber I the sand will settle upon the valve C, with the injurious effects before mentioned. It will 100 be observed that a chamber is also formed at M for the reception of sand that may not rise

above the working-valve C. Thus both the standing-valve C' and the working valve C are provided with chambers below them respectively for the reception of sand.

5 Having described our invention, what we claim as new, and desire to secure by Letters Patent, is—

1. In a deep-well pump, the combination with the working-barrel thereof, of a standing valve located above the bottom of the working-barrel, and of a loosely-fitting hollow plunger surrounding the standing valve, for the purpose set forth.

2. In a deep-well pump, the combination, 15 with the working-barrel of an inner tube attached at the bottom of the working-barrel and extending upwardly to form a chamber between it and the working-barrel, and of a standing valve attached to said inner tube, 20 substantially as described.

3. A deep-well pump consisting of the following elements—viz., a working-barrel whose upper end is disconnected from the education-pipe, a casing surrounding the working-barrel, a hollow plunger fitting snugly within the working-barrel and carrying a working-valve, and a standing valve mounted upon a pipe above the bottom of the working-barrel and loosely entering the hollow plunger, substantially as shown and described, and for the purposes 25 30 mentioned.

In testimony that we claim the foregoing we have hereunto set our hands this 12th day of May, 1882.

GEORGE A. KIMBALL.
LAURON H. KIMBALL.
